Primary Examiner — Sheryl Lane*Assistant Examiner* — Samantha N Wood(74) *Attorney, Agent, or Firm* — Plumsea Law Group,
LLC(57) **CLAIM**

The ornamental design for a figurine, as shown and described.

DESCRIPTION

FIG. 1 is a top isometric perspective view of a figurine showing the new design;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a top plan view thereof; and.

FIG. 7 is a bottom plan view thereof.

The broken lines and unshaded areas are included to illustrate parts of the article's appearance that form no part of the claimed design.
